UNITED STATES PATENT OFFICE.

GUSTAF RENNERFELT, OF SCRANTON, PENNSYLVANIA.

MEANS FOR OPENING AND CLOSING ELECTRICAL CIRCUITS.

No. 833,178.

Specification of Letters Patent.

Patented Oct. 16, 1906.

Application filed June 11, 1904. Serial No. 212,127.

To all whom it may concern:

Be it known that I, GUSTAF RENNERFELT, a subject of the King of Sweden and Norway, residing at Scranton, county of Lackawanna, 5 State of Pennsylvania, have made a new and useful Invention in Means for Opening and Closing Electrical Circuits, of which the following is a specification.

My invention is directed to improvements in means for opening and closing electric circuits in general, and especially such circuits as include electric motors.

The objects of my improvements are, first, to provide an electric switch or circuit-breaker having a time-constant whereby the circuit may be opened if it is subjected to a prolonged overload, but may remain closed if the overload is of short duration; second, to provide simple means for adjusting such 15 a switch so that the same device may be used for different loads; third, to provide means for magnetically blowing out the arc which is formed at this switch when it operates; fourth, to arrange the associated parts of the 20 switch so that it will be simple of construction and reliable in its operation; fifth, to provide means for closing and opening said switch; sixth, to prevent sparking at auxiliary contacts necessary for operating the 25 switch, the arrangement being such that all of the sparking is confined to the contacts of the switch and also such that waste of energy in the controlling solenoids or magnets used in the apparatus shall be reduced to a minimum; seventh, to provide novel means for 30 obtaining proper pressure for good contact on the controller and to provide that the same means shall extinguish sparking on the contacts of the controller, and also that they 35 shall serve to retain the controller in a certain position; eighth, to provide means for an automatic economical and reliable operation of the aforesaid circuit breaker and controller in general, and especially so that 40 no sparking shall occur in the auxiliary contacts necessary in the combination, all 45 sparking being confined to the contacts of the circuit-breaker, and also so that waste of energy in the solenoids or magnets used in the 50 apparatus may be reduced to a minimum. This especial feature—the reduction to a minimum of the energy wasted in the magnets—is of particular value, not only from the point of view of mere economy, in so far 55 as it tends to lessen the cost of construction, the cost of operating the apparatus, and the

cost of keeping it in repair, but it is also of especial value in that it makes it possible to operate the same magnets with either alternating or direct current.

My invention, which to some extent relates to improvements in apparatus described in United States Patent No. 769,406, granted to me September 6, 1904, will be fully understood by referring to the accompanying drawings, in which—

Figure 1 is a plan view of my novel switch. Fig. 2 is a sectional view thereof, taken on the broken line A A, Figs. 1 and 3, and as seen looking thereat from right to left in the direction of the arrows. Fig. 3 is a sectional view taken through Fig. 2 on the broken line B B and as seen looking thereat from left to right in the direction of the arrows. Fig. 4 is a sectional view taken through Fig. 2 on the line C C and as seen looking thereat from the top toward the bottom of the drawings in the direction of the arrows. Fig. 5 is a plan view of the controller. Fig. 6 is a sectional view thereof, taken through Fig. 5 on the line D D and as seen looking thereat from left to right in the direction of the arrows. Fig. 7 is an end elevational view as seen looking at Fig. 5 from the top toward the bottom of the drawings, the controlling-magnet for regulating the pressure between the contacting spring and the contact-blocks of the rheostat being shown in sectional view; and Fig. 8 is a diagrammatic view showing the application of my entire improvement in a system of motor-control and as connected with a water-tank adapted to be filled by a pump driven by the controlling-motor, the same figure illustrating also novel means for automatically disconnecting the motor from the circuit in the event of overload, due to any cause whatever, such disconnecting means being in the nature of a thermal device which is actuated by an abnormal flow of current therethrough.

Referring now to the drawings in detail, 1 represents the insulating-base of the switch, supported in any preferred manner.

2 and 3 represent the conducting-terminals of the switch, and 4 the yielding contact-arms thereof, made, preferably, of thin strips of sheet-copper and pivotally secured to the terminal 2 by a head 5, which is connected in turn by a link 6 to an operating-handle 7, provided with a strong spiral spring 8, the tendency of which is to rotate the handle 7 in the direction of the arrow, Fig. 2.

9 is a roller carried by the switch-head, and 10 is a locking-trigger for locking the switch in its closed position, said trigger being connected to an insulating-base 11, carried by an 5 armature-lever 12, located in front of the core 13 of a magnet 14.

15 is a retractile spring for the armature-lever 12, adapted to hold it in the position shown in Fig. 3, so that the trigger 10 will 10 rest against the roller 9 and lock the switch.

The plate 11 is of insulating material and also acts as a baffle plate or shield to separate the two terminals of the switch.

16 is a rubber buffer adapted to make a 15 cushion-stop for a lug 17, secured to the handle 7, when the switch is automatically released under the influence of the strong spring 8.

18 is a stationary carbon contact secured 20 to the terminal 3, and 19 is a movable carbon contact being carried by a yielding spring 20, secured to the head of the switch by screws, (see Figs. 2 and 4,) the function of said terminals being to interrupt the circuit without 25 danger of fusing the parts.

21 is the stationary contact-block for the free end of the yielding switch-arm 4, said block being of non-magnetic metal, preferably copper.

30 The extensions of the pole-pieces of the magnet 14 are so constructed and located with relation to the stationary contact 21 that the magnetic lines of force flowing therefrom will tend to extinguish the arc between 35 the movable and fixed terminals of the switch when the circuit is interrupted.

22 is an automatically-movable contact, made, preferably, of two thin strips of metal of different coefficients of expansion and soldered together.

40 23 is a carbon pencil secured in a slit in the manner shown in Figs. 2 and 3 and adapted to contact with the stationary contacts 24 or 48 in a manner to be hereinafter described, 45 which contacts 24 or 48 may also be provided with a carbon tip, if preferred.

The contact 22 may be secured directly to the base 1 by bolts, and the adjustable contact-point 24 is secured to the same base by a 50 standard 25, as shown. The contact 48 is similarly mounted.

Referring now to Figs. 5 to 7, inclusive, for a description of the controller, 26 represents the insulating-base, and 27 the controller-arm, pivotally secured thereto and carrying at its free end a sliding contact-plate 28, adapted to contact at one end against a series of rheostat segments or contacts 29, mounted upon the base 26 and connected to 60 successive coils thereof, and at the other end against the under surface of a contact-plate 30, secured at its opposite ends directly to the base, the arrangement being such that the free end of the controller-arm and the 65 sliding contact-plate 28, carried thereby, will

move between the plate 30 and rest upon the segments or contacts 29 as the arm is moved in either direction.

31 is a weight secured, as in Fig. 5, to the end of a lever carried by the controller-arm 7c 27 and adapted to normally hold said controller-arm in the "off position," so that all of the rheostat-coils are in circuit.

32 is an electromagnet secured at the outer end of the controller-arm 27 and provided 75 with an armature-lever 33, pivotally secured to its core, so that the short arm thereof shall support one end of the contact-plate 28 and press it against the under surface of the plate 30. The other end of the contact-plate 28 is 80 secured to the core of the magnet 32 and is pressed against the segments or contacts 29.

34 is a magnet secured to and carried by the controller-arm 27, and 35 is an iron arm pivotally secured to the controlling-arm, 36 85 being a section of a half-nut supported in a slot in the outer end of the arm 35 and in such manner that when the circuit is closed through the magnet 34 the screw-threads of the half-nut will be brought into mechanical 90 connection with the screw-threads of the screw 37 against the stress of a leaf-spring 38, carried by the arm 35 and resting on the pole of the magnet 34.

Referring now to Fig. 8, 50 designates an 95 electric motor which is arranged to drive a pump 70. This pump is connected to a reservoir or tank 71 by a pipe 72 and is arranged to pump water through a pipe 73 into another water-tank 74. A float 39 is attached to the inner end of a lever, which is pivoted upon one edge of this water-tank 74, the outer end of said lever being provided with an electric contact-plate adapted to make circuit between two contacts 42 when 100 the water has reached low level and at two additional contacts 43 when the tank has been filled. As illustrated in the drawings, the water is at low level and the pump-motor has just been connected in circuit by the closing of the automatic switch. This closing is effected by the lifting of the core 44 by the solenoid 45, which when contacts 42 are bridged will receive current by the following circuit: from the positive current-feeder 46 105 through the branch feeder 47, contacts 42, solenoid 45, branch feeder 47, adjustable contact 48, thermostatic device 49, branch feeder 50, armature 51 of the motor, to the negative current-feeder 52. Consequently 110 the solenoid 45 lifts the iron core 44, which is connected to the switch, so that the motor-circuit is closed from the branch feeder 50 through the yielding switch-arm 4, thus bridging between the terminals 2 and 3 to 115 the branch circuit 50, the contact-plate 30 of the rheostat, sliding contact-plate 28, the segments 29 of the starting resistance, and the motor-armature 51 to the negative main 52. The field-winding 53 of the motor will 120

receive current from contact-plate 30 of the rheostat, sliding contact-plate 28, coils of the magnet 32, conductor 54, contact 55, coils of the magnet 34, contact 56, winding 53, to the negative main 52. The windings of the magnets 32 and 34 are thus coupled in series with the shunt-field 53, and the magnet 34 will cause the sectional half-nut 36 to engage with the screw 37, so that when the 10 armature 51 of the motor starts this screw will be rotated in proper direction by reason of the belt 57 and pulley 58, as illustrated in Fig. 8, to cause the upper end of the controller-arm 27 to move from right to left, thus 15 gradually causing the contact-plate 28 to successively move across the rheostat segments or contacts 29, and to thereby cut the resistance-coils out of the motor-armature circuit. When all of the resistance is cut out, 20 the magnet 34 will be short-circuited through the contacts 55 and 56, and the half-nut 36 will therefore be disengaged, so that although the motor still continues to run and rotate the screw 37 the controller-arm will not be 25 advanced any farther. The magnet 32 still remains in circuit, so that its armature pivotally supported by the core will cause one of the free ends of the contact-plate 28 to bear with considerable friction against the under 30 surface of the curved plate 30, and additional friction will be exerted on the other end of the contact-plate 28 between the core and the rheostat-iron segments or contacts 29, the total amount of the friction being suf- 35 ficient to retain the arm in place against the action of the weight 31 so long as the current is flowing through the magnet 32. The core of the magnet 32 also performs another important function in that by reason of the 40 magnetic field set up as it passes over the rheostat segments or contacts 29, which are preferably of iron, the lines of force blow out any spark which may result as the plate 28 passes from segment to segment.

45 It will be noted that the solenoid 45 is so connected that the current flowing through it will be gradually decreased as the starting resistance is cut out by the rotation of the controller-arm 27 from right to left, and 50 no current will flow through said solenoid when all of this resistance is out of circuit. This feature constitutes an important part of my invention and is made the subject-matter of claims hereinafter. If this solenoid 55 were so connected that current passed through it all the time that the motor is running it would not be possible to open the switch by such simple means as I provide, and, furthermore, considerable energy would 60 be wasted by constantly maintaining the solenoid in circuit, whereas as now constructed when the starting resistance is all cut out of circuit both terminals of the solenoid are connected directly to the same current-main. If this solenoid were connected in

such manner that it became deenergized by the closing of contacts 2 and 3, it might possibly happen that it would not act a sufficient length of time to give proper pressure on the arm 7 and cause the locking of the switch, 70 which occurs, as is illustrated in Fig. 3, when the trigger 10 passes behind the roller 9, and I avoid any such possibility by connecting the solenoid 45 in the manner shown in Fig. 8 in shunt to the starting resistance or between 75 the plus main and the plus brush of the motor-armature, so that by reason of the variable drop of potential in the starting resistance I gain a result such that there will be sufficient current through the solenoid to 80 close the switch with certainty and yet prevent waste of energy in the solenoid while the motor is running.

Suppose now that the water has risen in the tank to its extreme limit and that the 85 contact-plate 41, carried by the pivoted lever controlled by the float 39, has made contact with the two contacts 43, owing to the rising of said float. When the circuit was interrupted at the contacts 42, no spark occurred 90 because, as before stated, no current was flowing through the solenoid 45, there being no difference of potential between the ends of its coil. When the water has risen, therefore, to the highest level and the contacts 43 95 established, as stated, this will cause a current to flow through the branch circuit 50 from the positive main 46 through the switch terminals 2 3 to the contact-plate 30, branch circuit 59, contacts 43, branch circuit 59, 100 coils of the magnet 14, branch circuit 59, to the negative main 52, thus energizing the magnet 14 and causing the same to act upon the armature-lever, which controls the operation of the trigger 10, thereby releasing the 105 roller 9 and allowing the spring 8, which controls the opening of the switch, to quickly remove the free end of the yielding contact-arm 4 from the stationary copper contact-bar 21 and also the carbon-terminal 19 from the 110 stationary carbon-terminal 18 (following later) opening the circuit without arcing. When the main circuit is thus finally opened, the magnet 32 is deenergized, and the counterweight 31 restores the controller-arm 27 to 115 its off position—that is, the position shown in the diagrammatic view, Fig. 8—and replaces all of the starting resistance in the motor-circuit. During this movement of the controller-arm 27 there is only little pressure 120 and friction between the sliding contact-plate 28, the rheostat-segments 29, and plate 30, since the magnet 32 has been demagnetized.

If the motor should happen at any time to 125 be subjected to a prolonged overload caused, for instance, by a hot journal-bearing, the circuit will be opened in the following manner: The thermostatic device 22 is so combined with the circuit that it is heated by the 130

current, and when it reaches a certain temperature it establishes a contact 22 24, which, as clearly seen from the diagram, will have the same effect on the switch as has the 5 closing of the contacts 43, the switch will be opened, the motor will stop, and the starting resistance will be reinserted into the motor-circuit. The preferred form of this thermostatic device consists of a metallic strip 10 made of two metals of different coefficients of expansion for heating—such, for instance, as copper and zinc—said metals being soldered together. The strip is then made, preferably, in the bent form, as shown, which occupies 15 less room than a straight form of strip would, and is included in the circuit so that it is traversed and heated by the main current or by a definite amount of the main current. A 20 resistance 60 may be connected in shunt to the strip 22 to take a part of this current. When the strip 22 is heated, it assumes a curved shape, and the contact 24 is so adjusted that it will be touched by the strip when it has reached a certain temperature. 25 When this happens, the magnet-winding 14 will receive current through the following circuit: from the plus main 46, through branch conductor 50, terminal 2, yielding switch-arm 4, terminal 3, conductor 50, plate 30 30, sliding contact-plate 28, conductor 50, thermostatic device 22, contact-point 24, branch conductors 61 and 59, coils of the magnet 14, to main 52. Consequently the trigger 10 is withdrawn and the switch opened 35 as before by the action of the spring 8.

Upon separation of the contacts 22 24 there will be no spark there, since the circuit is already broken on the switch at 19 18. A 40 push-button or similar device 62 may be arranged in a branch circuit 63, whereby the switch can at any time and from any distance be opened manually, and it will be noted that the connection for this push-button is such that no spark will occur at its terminals, for reasons before pointed out.

It will be observed that the strip 22 cannot 45 make contact with the adjustable contacts 48 24 at the same time, and the solenoid 45 and magnet 14 can therefore never be energized through the contacts simultaneously. This would happen if there were permanent 50 connections from the solenoid 45 to the plus brush of the armature 51 and if the contacts 42 were established while the strip 22 was sufficiently hot to touch the contact 24. Such a condition would prevent the locking 55 of the switch by the trigger 10 and roller 9 and would cause arcing of the contacts 18 and 19. By connecting the solenoid 45, as 60 shown, to the contact 48 I effect the result that after the motor-circuit has been automatically opened, by reason of a prolonged overload, it will not be automatically closed again before some time has elapsed. This 65 time will be long enough to allow the thermostatic

device 22 to cool off sufficiently to establish the contacts 48 22, and during this time the motor, which is included in circuit with the strip 22, will also cool somewhat, so as to be better adapted to stand the overload 70 in case it should still exist when the circuit is established. Should a hot bearing cause the overload, the bearing will have a chance to cool, and the overload may perhaps have disappeared when the circuit is closed again, due 75 to the making of contact between the strip 22 and contact 48. It is preferable that the thermostatic device 22 should be closed, as indicated at 64, Fig. 8, not only for the purpose of keeping out dust and to prevent its 80 being tampered with, but also for the purpose of preventing it from cooling too quickly.

When an electric motor is started, it is always subjected to a heavy load, inasmuch as the starting-current is in excess of the normal 85 running-current. This excessive starting-current is of short duration, and its heating effect on the motor is not great unless the starting is frequently repeated. Neither will its heating effect be great on the thermostatic device 22, and for this reason this device will not act so as to open the circuit for an overload of such short duration as that due to starting. It will, however, open the circuit for an overload which lasts during 90 some time—that is, such a length of time as will endanger the motor and will cause the temperature of the thermostatic device to rise to the predetermined limit—and it is evident that such an overload may correspond 95 to a current which is much smaller than the starting-current.

It must be well understood that the mode of operation of the switch or circuit-breaker here described is very different from that of the well-known types of circuit-breakers which open the circuit when the current attains a certain strength and which when used in simple combination with an electric motor will not open the circuit for an overload due to a current smaller than the starting-current. It should also be noted with regard to the controlling devices shown as assembled in diagrammatic view in Fig. 8 that their operation is performed in a very economical manner in view of the fact that there is no energy wasted in the magnet-windings 14, 34, and 45, which are temporarily energized only at the time when they have to perform actual mechanical work. The only winding which utilizes continuously some amount of energy is 32, and as the force required of this magnet is not heavy it will be apparent that by properly designing the air-gap and other details of the magnet 115 32 the amount of energy there wasted can be limited to a mere trifle. It might be added that in case of cessation of the voltage at the mains 46 and 52 the switch will not be opened; but since the magnet 32 will become deener- 120 125 130

gized the arm 27 will be brought to its off position, where all the starting resistance will be reinserted into circuit with the motor. When the voltage again appears and the motor starts up, the resistance is again cut out from the circuit.

Having thus described my invention, what I claim, and desire to secure by Letters Patent of the United States, is—

- 10 1. In an electric circuit, the combination of a contact-block 21, a switch-arm 4, a magnet for moving the arm into contact with the block, means for energizing the magnet and automatic means for gradually decreasing to 15 zero the current in said magnet.
- 2. In combination with an electric motor having an armature, a circuit for the armature, a switch in said circuit, a latch for holding the switch closed, a spring for opening 20 the switch and a magnet arranged to release said latch, said magnet having a winding in direct shunt with the motor-armature.
- 3. In an electric motor, the combination of a contact-block, a switch-arm, a spring arranged to separate the switch-arm from the contact-block, a magnet arranged to move the arm into contact with the block against the action of the spring, means for energizing the magnet, and means for gradually decreasing the current in the magnet to zero; a 25 latch for holding the arm against the contact-block, and a magnet for releasing the latch.
- 4. In an electric motor, the combination of a contact-block, a switch-arm, a spring arranged to separate the switch-arm from the contact-block, a magnet arranged to move the arm into contact with the block against the action of the spring, automatic means for energizing the magnet, and means for gradually decreasing the current in the magnet to zero; a latch for holding the arm against the contact-block, a magnet for releasing the latch, and means for automatically energizing 30 said releasing-magnet.
- 45 5. In an electric circuit, the combination of a motor, a starting resistance therefor, an electrically-actuated starting-switch, a magnet arranged to close the starting-switch, said magnet having a winding connected in shunt to the starting resistance.
- 6. In combination with an electric motor, a device arranged to automatically stop the motor when said device is heated to a predetermined degree and to automatically start 55 the motor when cooled to a predetermined degree, the temperature of said device being arranged to be proportional to that of the motor.
- 7. In combination with an electric motor, 60 an automatic thermostatic device arranged to break the motor-circuit when current in said circuit is excessive, and to close said circuit after an elapsed time, the length of said time depending upon the amount of said excess current.

8. In combination with an electric motor having an armature, a starting-switch therefor, a latch for holding the switch closed, a spring for opening the switch, an electromagnet arranged to release the latch, said 70 magnet having a winding connected in shunt to the armature of the motor, and a thermostat in series with the motor-armature and arranged to be actuated by said current and arranged to close the circuit through the 75 magnet.

9. In combination with an electric motor, a resistance in series with the motor, a starting-switch for the motor, a magnet arranged to close said starting-switch, said magnet 80 having a winding connected in shunt to said resistance, and means for retaining the switch in its closed position.

10. The combination with a source of electrical supply, of a circuit, a thermostat in said 85 circuit arranged to be heated by current from said source of supply, a second electric circuit deriving current from said source of supply through the thermostat, a contact-piece located in said second circuit in close 90 proximity to the thermostat, and means for adjusting the relative position of the thermostat and the contact-piece.

11. The combination with a source of electrical supply, of a translating device connected to said source of supply, a thermostatic device in series with said translating device, a switch also in series with the translating device, a magnet having a winding and arranged, when energized, to open said switch, 100 a contact-piece located in the circuit of the magnet-winding and adapted to come into electric contact with the thermostat when the latter is heated to a predetermined degree, and means for adjusting the distance 105 between the thermostat and the contact-piece.

12. The combination with a source of electrical supply, of a translating device connected to said source of electrical supply, a thermostatic device in series with the translating device, a switch also in series with the translating device, a magnet having a winding and arranged, when energized, to close the switch, a contact-piece located in the circuit 110 of the magnet-winding and adapted to come into electric contact with the thermostat, and means for adjusting the distance between the thermostat and the contact-piece.

13. The combination with a source of electrical supply, a translating device connected to said source of supply, a switch in series with the translating device, a magnet having a winding arranged, when energized, to close the switch, said winding being also in series 115 with the translating device, means for retaining the switch in its closed position, a thermostat in series with the translating device, and means operated through the thermostat for opening the switch. 130

14. The combination of an electric motor having an armature, two contacts in series with the armature, a starting resistance, an electromagnet in series with the armature and in shunt to the starting resistance, means actuated by the electromagnet for closing the contacts, and means for retaining the contacts in closed position.

15. The combination of a motor, a circuit for the motor, means for closing the circuit, a thermostatic device dependent upon its temperature for delaying the time of the closing of said circuit, and means dependent on its temperature for opening the motor-circuit, the thermostatic device arranged to have its temperature proportional to that of the motor.

16. The combination of an electric motor, a starting-switch therefor, a magnet arranged, when energized, to close the switch, a second magnet arranged, when energized, to open the switch, circuits for the magnets, and a thermostat through which one or the other of said magnet-circuits may be energized, said thermostat being in series with the motor.

17. The combination of an electric motor, a starting-switch therefor, a magnet arranged, when energized, to close the switch, a second magnet arranged, when energized, to open the switch, circuits for said magnets, an automatic switch for closing one or the other of said magnet-circuits, and a thermostat in circuit with the motor and arranged to control said magnet-circuits.

18. The combination of an electric motor, a starting-switch therefor, an automatic rheostat in the motor-circuit, a magnet arranged, when energized, to close the starting-switch, a second magnet arranged, when energized, to open said switch, circuits for said magnets, a pump arranged to be driven by the motor, a tank hydraulically connected with the pump, a switch arranged to be actuated by the level of water in said tank to close the circuit of said first magnet when the water-level is low and to close the circuit of said second magnet when the water-level is high, and a thermostat in circuit with the motor and arranged to control said magnet-circuits.

19. In combination with an electrical source of supply, a circuit deriving current therefrom, a metallic strip included in said circuit and arranged to bend when heated by the current, a contact in close proximity to the strip, and means for adjusting the position of the contact relative to the strip, said contact being arranged to be brought into or out of electric connection with the strip upon a movement of the strip, and means for avoiding breaking of any current at said contact.

20. In combination with an electric circuit, a switch therefor, means for retaining the switch in its closed position, a magnet,

and means coöperating with the magnet to open the switch when the magnet is energized, a thermostat included in the circuit, and through which the magnet may be energized, and a resistance in shunt to the thermostat so arranged that a definite part of the current in the circuit will flow through the thermostat.

21. The combination of a switch, a spring arranged to open the switch, a magnet arranged to close the switch against the action of the spring, a circuit for said magnet, a contact-switch arranged to be closed and opened in said circuit, means for holding the first switch closed, a magnet for releasing the holding means, a circuit for the releasing-magnet, a contact-switch arranged to be closed and opened in the releasing-magnet circuit, said circuits and contacts arranged to avoid the breaking of any current at either of said contact-switches.

22. The combination with a source of electrical supply, of a thermostat arranged to be heated by a current from said source of supply, an electric circuit deriving current from said source of supply through the thermostat, a contact-piece located in the circuit in close proximity to the thermostat, a carbon piece attached to the thermostat opposite to said contact-piece, and means for adjusting the relative position of the thermostat and the contact-piece.

23. The combination with a source of electrical supply, of a thermostat arranged to be heated by current from said source of supply, an electric circuit deriving current from said source of supply through the thermostat, a contact-piece located in the circuit in close proximity to the thermostat, and means for adjusting the relative position of the thermostat and the contact-piece.

24. In combination with an electrical source of supply, a circuit deriving current therefrom, a metallic strip included in said circuit and arranged to bend when heated by the current, a contact included in the circuit in close proximity to the strip, and means for adjusting the position of the contact relative to the strip.

25. In combination with an electric circuit, an automatic thermostatic device included in the circuit and arranged to open the circuit after a time limit when the current in said circuit reaches a predetermined amount, and to close the circuit after the elapsed time, and means for varying the time limit.

In testimony whereof I have signed my name to this specification in the presence of two subscribing witnesses.

GUSTAF RENNERFELT.
